(57) **CLAIM**

The ornamental design for a container for trapping an insect, as shown and described.

DESCRIPTION

FIG. 1 is a perspective view of an upper portion of the container for trapping an insect showing the new design; FIG. 2 is a front elevation view of the upper portion shown in FIG. 1.

FIG. 3 is a rear elevation view of the upper portion shown in FIG. 1.

FIG. 4 is a right side elevation view of the upper portion shown in FIG. 1.

FIG. 5 is a left side elevation view of the upper portion shown in FIG. 1.

FIG. 6 is a top plan view of the upper portion shown in FIG. 1.

FIG. 7 is a bottom view of the upper portion shown in FIG. 1.

FIG. 8 is a perspective view of the container for trapping an insect including the upper portion shown in FIGS. 1-7.

FIG. 9 is a front elevation view of the container for trapping an insect shown in FIG. 8.

FIG. 10 is a rear elevation view of the container for trapping an insect shown in FIG. 8.

FIG. 11 is a right side elevation view of the container for trapping an insect shown in FIG. 8.

FIG. 12 is a left side elevation view of the container for trapping an insect shown in FIG. 8.

FIG. 13 is a top plan view of the container for trapping an insect shown in FIG. 8; and,

FIG. 14 is a bottom view of the container for trapping an insect shown in FIG. 8.

The ornamental design which is claimed is shown in solid lines in the drawings. Broken lines, if present in the drawings, are for illustrative purposes only and form no part of the claimed design.
